(57) **CLAIM**

The ornamental design for a cap for a medical injector having a hemispherical portion, as shown and described.

DESCRIPTION

FIG. 1 is a perspective view of a cap for a medical injector having a hemispherical portion in accordance with the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view of the cap for a medical injector of FIG. 1 shown engaged with an injector.

The broken lines representing portions of the interior of the cap shown in FIGS. 1 and 7 and the injector shown in FIG. 8 represent disclaimed subject matter and form no part of the claimed design.

1 Claim, 8 Drawing Sheets
